UNITED STATES PATENT OFFICE.

PHILIP A. EMERY, OF CHICAGO, ILLINOIS.

SOFA-BED.

SPECIFICATION forming part of Letters Patent No. 299,528, dated June 3, 1884.

Application filed July 5, 1883. (No model.)

To all whom it may concern:

Be it known that I, PHILIP A. EMERY, a citizen of the United States, residing at Chicago, in the county of Cook and State of Illinois, 5 have invented certain new and useful Improvements in Combined Sofa and Bed; and I do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

My invention relates to a combined sofa and 15 bed; and it consists in the construction, arrangement, and combination of the various parts, substantially as herein set forth, described, and claimed.

Referring to the drawings, in which similar 20 letters denote similar parts, Figure 1 is a perspective view of my improvements when used as a sofa. Fig. 2 is a perspective view, showing the parts adjusted as a bed. Fig. 3 is a detail view of a part of the means employed 25 to pivot the bed-frame to the outer frame.

In the drawings, A represents the outer frame that holds or contains the elements of 30 my invention. Said frame consists of the uprights or side pieces, *a a*, front piece, *a'*, and top *a²*. The frame A thus formed is strengthened by brackets *a³* at the top, and cross-bar *a⁴* at the bottom and back side thereof, as shown in Fig. 2. By the above-described construction it will be readily seen 35 that a strong, light, and durable frame is provided without the necessity of an entire back- 40 ing. The side pieces, *a a*, are provided at their lower forward edges with projecting portions *a⁵*, between and to which the sofa-seat B is secured. Said sofa-seat may be upholstered, 45 as shown, or finished in plain or perforated wood, or otherwise, as desired. The projecting portions *a⁵* of the sides are at their tops provided with arm-rests *a⁶*, the rear ends of which curve upward and join the forward edges of the sides proper.

If desired, the space between the sofa-seat B may be used as one compartment, or may,

as shown, have drawers *b* placed therein, the fronts of which bear against the piece *a'*.

C represents a rectangular frame, pivoted to the inner surfaces of the side pieces, *a*, by a bar, *C'*, and bearing-plate *C²*, as shown in Fig. 1, the lower surface of said frame being finished like the seat, or otherwise, and when in an elevated position forms the back of the sofa, as shown in Fig. 1. The bar *C'* extends from end to end of said frame behind said upholstered surface, and in the plane of the upper surface of the sofa-seat, (see Fig. 1,) the ends of said bar resting in slots in the bearing-plates *C²*, secured to the inner surfaces of the sides *a*, whereby the bed-frame may be easily lifted therefrom.

D D' represent the head and foot boards of the bedstead, said boards being pivoted to the sides *a*, as shown at *d*, Fig. 1. The inner ends of the boards are cut away at their lower edges, as shown by dotted lines at *d'*, Fig. 2, whereby when said boards are thrown up they rest against the rod *C'*. As will be seen from the drawings, the outer or upper ends of the boards D D' are longer and heavier than the rear ends thereof, and when the bed-frame is turned down said boards fall to their proper position.

E represents a board hinged at *e* to the rear side board of the bed-frame C, said board being provided at its upper edge and at the rear surface thereof with a pivoted bar *E'*, to the outer end of which is centrally pivoted a swinging cross-bar, *E²*. The board E, when the bed is in use, is in the position shown in Fig. 2, and when the bed is closed its position is shown by dotted lines in the same figure. The board E and its connected bars *E' E²* bear upon and keep the mattress and bed-clothing in place, the hook *d²* upon the forward side board of the bed serving to hold said bars *E'* and *E²* in place.

F represents legs attached to the forward side board of the bed-frame, near the ends thereof, as shown.

The operation of my invention will be readily understood without further description.

What I claim is—

1. The combination of the frame A, con-

constructed substantially as shown and described, with the bed-frame C and head-board D, the latter being reduced at its inner end, and adapted to operate as set forth, said frame and head-board being independently pivoted to the frame, as shown and described.

2. The combination, with the pivoted bed-frame C, of a hinged side board, E, hook d^2 ,

and the folding bars E' and E'', as and for the purpose set forth.

In testimony whereof I affix my signature in presence of witnesses.

Witnesses: PHILIP A. EMERY,

MARY A. EMERY,

GRACE D. EMERY,

JOHN T. DELANY.
